CLAIM

The ornamental design for the inflatable water hammock as shown and described.

DESCRIPTION

FIG. 1 is a top perspective view of the inflatable water hammock showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof; and,

FIG. 8 is a bottom perspective view thereof.

The broken line showing of the inflatable water hammock is for the purpose of illustrating portions of the article that forms no part of the claimed design.

1 Claim, 6 Drawing Sheets
